UNITED STATES PATENT OFFICE

EDWARD JOSEPH BEAN, OF POPLAR, LONDON, ENGLAND

BOLLARD

Application filed August 14, 1928, Serial No. 299,610, and in Great Britain August 15, 1927.

This invention relates to bollards or mooring posts and more particularly to bollards or mooring posts for use upon the edge of a dock, jetty or the like, the improved bollard or 5 mooring post according to the invention being, however, also applicable for use upon a ship, yacht or pontoon or the like.

The present invention has among its objects to provide an improved construction of 10 bollard or mooring post whereby certain disadvantages due to the ropes or hawsers slipping up or down the post are obviated, and by the use of which one or more of the ropes or hawsers may be effectively secured with the 15 minimum of turns.

According to the invention a bollard or mooring post comprises a vertically disposed pillar or base of substantial cross section having at its upper part a pair or a plurality 20 of upwardly extending splayed arms or posts, and having outwardly and rearwardly projecting parts around two angles of the base and at or adjacent the junction of the lower ends of the respective arms or posts with the 25 pillar or base, which projecting parts are preferably somewhat undercut or otherwise formed so that their under-faces are inclined downwardly from the root to the extremity thereof. The pillar or base and the arms or 30 posts may be of any suitable cross-sectional shape and the laterally projecting parts may be also of any suitable shape, the bollard or mooring post being preferably in the form of a hollow casting integrally provided with the 35 arms or posts and with the laterally projecting parts. The pillar or base may be provided with a laterally extending flange at its lower end by which it may be bolted in position, and if desired may have a downward 40 extension integrally or otherwise secured thereto, which extension is adapted to be embedded in the concrete or other material of which the dock is constructed, or to be 45 bolted to additional supports at a lower level, as when the bollard or mooring post is used upon a ship or yacht.

The invention further comprises the features of construction herinafter described.

50 The invention is hereinafter described with

reference to the accompanying drawings, in which:—

Figure 1 is a rear elevation of a bollard or mooring post according to the invention;

Figure 2 is a side elevation corresponding 55 to Figure 1;

Figure 3 is a front elevation corresponding to Figures 1 and 2;

Figure 4 is a corresponding plan, and

Figure 5 is a section on the line 5—5, Figure 60 1.

According to the illustrated embodiment of the invention, the bollard or mooring post comprises a pillar or base *a* which is conveniently hollow and of substantially rectangular 65 cross-sectional shape, as shown in Figure 5. The pillar or base *a* may be provided with a laterally extending flange *a'* at its lower end by which it may be bolted to the dock or the like or to the deck of a ship or other foundation, and if necessary or desirable, may also be provided with a downwardly extending part 70 *a''* which may be integral with the pillar or base or may be constructed separately and bolted thereto, and which is preferably in the 75 form of a downwardly tapering hollow rectangular pillar. The downwardly extending part *a''* may be provided at its lower end with a laterally extending flange *a'''* by which it 80 may be bolted to an additional support, or by which it may be keyed into a concrete or other foundation.

The pillar or base *a* is extended upwardly in the form of a pair of posts *b* which preferably 85 diverge slightly upwardly away from one another, and may be of circular, elliptical or other suitable cross-section, for example, somewhat as indicated in Figure 4. The upwardly extending posts *b* are preferably 90 formed integral with the pillar or base *a* and the latter is provided with a pair of integral outwardly and substantially rearwardly projecting arms *c* which extend from positions at or adjacent the junction of the posts *b* with the pillar or base *a*, the projecting arms *c* 95 preferably diverging outwardly from one another. The arms *c* may be of any suitable shape. Thus, they may be substantially semi-circular in plan and provided with 100 downwardly curved upper faces terminating 63

in a comparatively sharp corner at their junction with the under faces thereof, somewhat as indicated in the drawings. The under faces of the arms *c* are practically inclined slightly downwardly from the root to the outer edge, as indicated at *c*¹ in Figure 3, and adjacent their junction with the pillar or base *a* are curved and suitably shaped, as at *c*², to accommodate a rope or hawser.

10 The pillar or base *a*, the posts *b* and the projecting arms *c* are preferably formed in one piece by casting and are preferably hollow as shown.

15 It will be understood that by the use of a bollard or mooring post according to the invention, it is immaterial whether the rope or hawser attached to the ship is substantially above or below the level of the deck, inasmuch as by carrying the rope or hawser beneath or above one of the arms *c* and around 20 the respective post *b*, the rope or hawser cannot slip up or down upon the bollard or mooring post and is, moreover, very easily manipulated, as when checking and warping. For example, where the ship to which 25 the rope or hawser is attached is very high above the dock, the rope or hawser may be passed round the bollard as indicated on the left hand side of Figure 1, or alternatively, the rope or hawser may be passed downwardly from the ship underneath the left hand 30 arm *c*, through the space between the two posts *b*, and around the rear of the right hand post *b*, this arrangement being especially useful when checking or warping. Where 35 the rope or hawser is attached to a ship below the level of the dock, the rope or hawser may be disposed, for example, as indicated on the right hand side of Figure 1, the rope or hawser being passed from the ship over 40 the projecting arm *c*, round the underface thereof, through the space between the posts *b*, round the rear of the respective post *b* and then back round the projecting arm *c* 45 in the reverse direction. Alternatively, two ships may be moored to the same bollard or mooring post by passing the looped ends of the mooring ropes through the space between the posts *b* and round the projecting arms *c*, somewhat as indicated in Figure 3. It 50 will be appreciated that two separate mooring ropes or hawsers may be secured to the bollard without, however, jamming one upon the other so that the ropes or hawsers are capable of being manipulated independently. 55

60 The bollard or mooring post according to the invention is applicable for a variety of purposes. Thus, it may be employed on yachts where a vertical or horizontal lead is required, such as for the peak halyards or head sheets. It will be noted that it is unnecessary to take more than one complete turn of the rope around any part of the bollard, so that thus the formation of kinks in 65 the rope or hawser may be avoided, and wear

and tear thereon reduced and the life of the rope accordingly increased with resultant economy.

It will be understood that the invention is not limited to the construction hereinbefore 70 described. For example, the projecting arms *c* may be of any other suitable form, as in the form of thick rods projecting outwardly and rearwardly and somewhat downwardly 75 from the junction of posts *b* with the pillar or base *a*. Furthermore, the bollard may be made in two or more parts which may be bolted or otherwise secured together in any suitable manner, while the downwardly extending part *a*², where such part is provided, so 80 may be of any other suitable form. The device may also be made of any other metal or material for instance wood or reinforced concrete. In a slightly modified construction the post *a* may be provided with three or 85 more upstanding arms *b* as will be readily understood.

What I claim is:—

1. A bollard or mooring post comprising a vertically disposed pillar, a plurality of 90 splayed posts rising from the upper end of the pillar, and laterally projecting arms adjacent the junction of the lower ends of the posts with the pillar, the arms having their under faces inclined downwardly from the 95 pillar to their extremities.

2. A bollard or mooring post comprising a vertically disposed pillar, a plurality of splayed posts rising from the upper end of the pillar, lateral diverging arms projecting 100 from one side of the pillar at the junction of the posts therewith, the upper surfaces of said arms being curved downwardly and meeting the under surfaces thereof in a sharp corner, and a laterally extending anchoring flange on the pillar below said arms. 105

In testimony whereof I have hereunto signed my name.

EDWARD JOSEPH BEAN.
